INVENTOR.

L. J. Bazzoni
By his Attorney,
Robert McDonald

UNITED STATES PATENT OFFICE.

LEWIS J. BAZZONI, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

MANUFACTURE OF SHOES.

1,366,898.

Specification of Letters Patent. Patented Feb. 1, 1921.

Application filed February 28, 1920. Serial No. 361,975.

To all whom it may concern:

Be it known that I, LEWIS J. BAZZONI, a citizen of the United States, residing at Swampscott, in the county of Essex and

5 State of Massachusetts, have invented certain Improvements in the Manufacture of Shoes, of which the following description, in connection with the accompanying drawings, is a specification, like reference characters 10 acting on the drawings indicating like parts in the several figures.

This invention relates to the manufacture of shoes and is herein set forth illustratively, but not by way of limitation, with particular reference to the stiffening of the shank 15 portions of shoes.

It is usual in the manufacture of shoes to provide a shank stiffener, frequently of metal, which extends from the heel seat portion 20 of the shoe through the shank toward the ball line. It is usual in the manufacture of turn shoes to attach this metal stiffener to a leather or fiber member which is of a contour corresponding to that of the rear 25 portion of the sole thereof and which itself is attached to the sole by appropriate means. While such a stiffener is decidedly helpful in maintaining the shape of the shoe it does not have the same stiffening effect that it 30 would have if applied directly to the sole itself.

It is an object of my invention, accordingly, to provide for the attaching of such a stiffener to the outsole of a shoe and to 35 attach the stiffener, moreover, in a manner which will be applicable, though by no means limited, to the manufacture of turn shoes. To do this the stiffener must be capable of attachment to the sole after the 40 shoe has been turned since it is evident that a sole with a metal shank stiffener attached thereto could not be turned. My invention provides for such attachment after the shoe has been turned.

45 A further object of my invention is to provide for the utilization of such a stiffener in a rubber soled turn shoe.

The attachment of a metal shank stiffener to the outsole of any single soled shoe, or to 50 the sole of a turn shoe, by nails or tacks has heretofore been precluded by reason of the undesirability of the clenching of the nails or tacks on the exposed outer surface of the sole. An object of my invention,

accordingly, is to provide for the clenching 55 within the substance of the sole of suitable fasteners which may be used for this purpose.

It is a further object of my invention to do this in a manner which is applicable to 60 turn shoes, in which case the shank stiffener must be attached to the sole after the shoe has been turned.

With these and other objects in view my invention contemplates the provision of a 65 shank stiffener having a deflecting surface or surfaces which, when the stiffener is placed in contact with the sole of a shoe, will deflect a suitably driven fastener, such, for example as a staple, so that its prong 70 or prongs will extend at an acute angle into the sole and be then somewhat bent so that the ends of the fastener embedded in the sole will be arranged approximately parallel to the surface thereof, and, if the sole 75 is of rubber, beneath the upper layer of reinforcing fabric of the sole.

With the foregoing and other objects in view the invention will now be described with reference to the accompanying drawings and pointed out in the claims.

Figure 1 is a perspective view of a shoe partly broken away so as more clearly to show the invention;

Fig. 2 is a cross-section through the shank 85 of the sole of the shoe of Fig. 1; and

Fig. 3 is a section through the same portion of a slightly modified shoe.

In the drawings, 10 represents the sole of a turn shoe, shown in Figs. 2 and 3 as of 90 rubber and provided at or near its upper surface with a layer of fabric 12, such as canvas, for the purpose of reinforcing the same. A depression 14 is provided at about the middle of the shank portion of the shoe, 95 for instance by molding, if the sole is of rubber.

The shank stiffener of the invention consists of a strip 16 of suitable metal provided at its median portion with a pair of 100 slots 18 and having the material of the body of the shank adjacent to and between the slots deformed as at 20, so as to provide a pair of inclined portions the lower parts of which may be positioned in the depression 14 of the sole and which will deflect the ends of a fastener such as a staple 22 when the latter is placed with its ends in contact

therewith and is driven by a suitable tool or machine. These deformed surfaces are so arranged that as the fastener is driven its points will be deflected so as to enter the sole at an acute angle to the upper surface thereof and will take up their final position approximately parallel to that surface as clearly shown in Figs. 2 and 3.

5 An additional fastener such as a tack or nail 24 may be provided to attach the rear portion of the shank stiffener to the sole.

10 In the modification of Fig. 3, a depression 26 extending the entire length of the shank stiffener is molded or otherwise 15 formed in the sole so that the upper surface of the shank stiffener will be flush with the upper surface of the sole, and this depression is provided with a deeper portion 28 to receive the deformed portion of the shank 20 stiffener.

15 Although the invention has been described with reference to the illustrated turn shoe, it is to be understood that this is to be taken only as an exemplification thereof, and that 25 the invention is not to be limited in its scope thereby, being clearly applicable to the manufacture of shoes of other types.

20 Having described my invention, what I claim as new and desire to secure by Letters 30 Patent of the United States is:

1. The method of uniting a sole and a shank stiffener which comprises placing the shank stiffener in contact with the surface of the sole and then driving a fastener 35 through the shank stiffener and into the sole and at the same time deflecting it as it enters the sole at an acute angle to the upper surface of the sole thereof and embedding the portion thereof which penetrates 40 the sole between the upper and lower surfaces of the sole.

2. The method of uniting a sole and shank stiffener which comprises placing the shank stiffener in contact with the surface of the sole and then forcing the prongs of a multiple-pronged fastener into the sole in diverging directions, while straddling a portion of the shank stiffener, and embedding the end portions of the prongs in the sole.

45 3. The method of uniting a sole and a shank stiffener which comprises placing a shank stiffener in contact with the surface of the sole and then forcing the prongs of a multiple-pronged fastener through the shank stiffener and into the sole and at the same time deflecting said prongs so that they enter the sole and assume a final position 55 between the surfaces of the sole and approximately parallel thereto.

60 4. The method of uniting shoe parts which consists in placing said parts in contacting relation, and driving a multiple-pronged fastener through one and into another of said parts and at the same time lat-

erally deflecting the prongs of the fastener 65 in opposite directions and embedding them in said last-named part approximately parallel to the surface thereof.

5. A shank stiffener provided with an aperture and an inclined surface adjacent thereto to deflect a fastening member as the latter is driven into a shoe sole.

6. A shank stiffener provided near its median portion with a pair of parallel slots and having a pair of inclined, diverging 75 fastener deflecting portions adjacent the said parallel slots.

7. A shank stiffener having a pair of apertures with a pair of oppositely inclined surfaces adjacent thereto to deflect the 80 prongs of a staple as the latter is driven through the aperture into a shoe sole.

8. A shank stiffener provided near its median portion with a pair of slots and having a pair of inclined, diverging, fastener deflecting portions adjacent to said slots and a fastener receiving opening adjacent to its rear end.

9. The combination of a sole, a shank stiffener contacting therewith and provided 90 with a pair of inclined deflecting surfaces, and a fastener straddling said deflecting surfaces and extending into the sole in a direction approximately parallel to the surface thereof.

95 10. The combination of a sole, a shank stiffener contacting therewith, and a fastener straddling a portion of the shank stiffener and having its ends embedded in the sole and approximately parallel to the 100 surface thereof.

11. A shoe having a rubber sole with a sheet of reinforcing fabric embedded therein, a shank stiffener contacting with said sole and provided with a pair of inclined 105 deflecting surfaces and a fastener contacting with the deflecting surfaces of the shank stiffener and penetrating the reinforcing fabric and the rubber of the sole, and having its ends embedded in the sole beneath 110 the reinforcing fabric.

12. A shoe having a sole, a shank stiffener therefor provided at its median portion with a pair of fastener deflecting surfaces, and a pronged fastener engaging the 115 deflecting surfaces of the shank stiffener and having its prongs embedded in the sole and deformed and flattened by the action of the deflecting surfaces so that its ends are positioned in the sole approximately parallel to the surface thereof.

13. A shoe having a sole with a depression therein, a shank stiffener in contact with the sole and provided with a pair of parallel slots and having the material between the slots deformed and depressed so as to occupy the depression in the sole, and a fastener contacting with the deformed

portion of the shank stiffener and extending therefrom into the sole at an acute angle to the surface thereof.

14. A shoe having a sole, a shank stiffener therefor, a fastener for attaching the rear portion of the shank stiffener to the sole, said shank stiffener being provided at its median portion with a pair of fastener deflecting surfaces, and a staple engaging

the shank stiffener and having its prongs 10 embedded in the sole and deformed and flattened by the action of the deflecting surfaces so that its ends are positioned in the sole approximately parallel to the surface thereof. 15

In testimony whereof I have signed my name to this specification.

LEWIS J. BAZZONI.
